KNITTING MACHINE

Robert H. Lawson and Paul W. Bristow, Laconia,
N. H., assignors to Scott & Williams, Incorporated,
Laconia, N. H., a corporation of Massachusetts

Application October 1, 1942, Serial No. 460,378

39 Claims. (Cl. 66—131)

This invention relates to a knitting method and machine, and in particular relates to means for feeding yarns to the needles thereof and the manipulations of said yarns.

In the incorporation of rubber or other elastic yarns in knitted fabric, yarn changes must be provided in such fashion that the elastic yarn is laid in during the knitting of other yarn or yarns and may be taken out at any desired times. In particular, it is sometimes required that the elastic yarn be introduced in alternate courses, or periodically for single or perhaps double courses only.

One of the objects of the invention is the provision of an arrangement for accomplishing this, particularly adapted to a type of yarn change mechanism which is extensively used in connection with a superposed cylinder type of machine. In accordance with this phase of the invention, the elastic yarn control is provided in the form of a simple accessory to the conventional yarn changer.

The invention further relates to the provision of a yarn feeding mechanism comprising upper and lower series of yarn fingers with provisions for effecting the proper presentation of yarns to the needles by all of such fingers. This includes specifically the provision of a yarn guide for insuring substantially the identical path of movement of the yarn to the needles irrespective of the finger which effects the feeding. By the provision of upper and lower banks of feeding fingers, they and their clamps and cutters may be brought closer to feeding position, thereby producing shorter yarn ends in the fabric.

Further objects of the invention relate to the manipulation of the yarns in the formation of stitches.

These and other objects of the invention, particularly relating to details, will become apparent from the following description, read in conjunction with the accompanying drawings, in which:

Figure 1 is a fragmentary elevation of a portion of a knitting machine of superposed cylinder type embodying the features of the invention;

Figure 2 is a fragmentary view showing, in particular, the arrangement of a cam follower for controlling movements of a yarn feeding finger;

Figure 3 is a fragmentary perspective view showing the selective means for effecting yarn changes and indicating certain conventional auxiliary devices;

Figures 4 to 8, inclusive, are diagrammatic sec-

tional views indicating in particular various steps involved in effecting yarn changes;

Figure 9 is a similar view but showing specifically the mechanism for effecting elastic yarn changes;

Figures 10 to 13, inclusive, are diagrams of various positions of the selecting means for effecting yarn changes;

Figure 14 is a diagrammatic elevation showing in particular the mechanism for clamping and cutting the yarns;

Figure 15 is a diagrammatic perspective view showing the controlling means for bodily swinging the yarn fingers during yarn changing operations;

Figure 16 is a fragmentary perspective view showing in particular the guidance of a yarn being fed to the needles and the positions taken by the yarn fingers in effecting the feed;

Figures 17 to 19, inclusive, are fragmentary diagrammatic views illustrating the fashion in which the yarns are handled by special cooperation of needles and sinkers resulting in acceleration of seizure of an ingoing yarn; and

Figures 20 and 21 are fragmentary diagrammatic views illustrating the action of an extended nose of a sinker in preventing undesired downward movements of loops during the picking of the needles into action in heel and toe knitting.

The type of machine to which the invention is applied is of the superposed cylinder type shown particularly in the patent to Bentley 1,838,651, dated December 29, 1931. In this type of machine, there are provided lower and upper cylinders indicated at 2 and 4, respectively, in Figure 1, carried by a suitable frame 6, within slots in which cylinders there slide double ended needles under the control of jacks which also slide within the needle slots. In the formation of plain fabric, all of the needles are located in the lower cylinder, their lower hooks being engaged by the jacks therein, and their upper hooks and latches at this time serve to seize the yarn and form stitches. In the formation of rib fabric, or for the formation of fabric involving other reverse concatenations of loops, certain of the needles may be located in the upper cylinder, being engaged therein by sliders carried by the upper cylinder, in which case their lower hooks and latches are active in the formation of loops.

The fact that the needles thus acting at times in both the upper and lower cylinders form a cage precluding the movement of any elements across the needle circle necessitates taking special

precautions to insure that the yarns are properly engaged by the needles.

Accordingly, the yarn fingers are given special elaborate movements such as described in said Bentley et al. Patent 1,838,651, and as will be referred to in greater detail hereafter.

A bracket 8 is mounted upon a vertical shaft to which is secured a lever 10 having a horizontally extending arm (see Figure 15). On this bracket 8 there are supported in upright guides, of which one is indicated at 12, a plurality of rods 14 terminating in yarn eyes and constituting yarn feeding fingers. These rods or fingers, as they will be hereafter referred to, are mounted for longitudinal sliding movement and are also capable of oscillation about their axes by reason of the engagement of laterally extending pins 18 carried by them through cam slots 20, formed in an upright plate 13 located alongside the fingers. At their rear ends the various fingers are engageable by the laterally extending upper ends of actuating levers 16 whereby they may be moved longitudinally against the action of springs 22 individual to the fingers. In the present case, this arrangement is true of the upper five of the 25 fingers, but in the case of the lowermost, which is adapted to feed the elastic yarn, instead of a long lever 16, there is provided a short lever 30, mounted concentrically with the other levers and similarly moved, but connected through a link 28 to another lever 26 which is, in turn, connected through a flexible link 24 to the pin 18 of the lowermost finger. This arrangement is provided solely for convenience and to secure the necessary range of movement through a magnification afforded by the lever combination.

Reference to Figure 2 will show the arrangement whereby a proper adjustment of the positions of the yarn feeding fingers may be secured. To each of the levers 16, as well as to lever 30, there is pivoted at 34 upon a shoulder screw adjustably clamped in a slot an individual cam follower 32 (designated 38 in the case of lever 30), the angular position of which with respect to the lever is adjustable by means of an abutment screw 36. It will be evident that through this arrangement the position of the feeding eye of a finger when it is in feeding position may be finely adjusted, while by reason of the slot adjustment the timing of operation may be accurately fixed.

A stationary shaft 40 has journalled thereon a cam and ratchet assembly for each of the yarn feeding fingers, including that which handles the elastic yarn. In Figures 4 to 9, inclusive, are shown certain of the elements of each of these assemblies. Each comprises a ratchet 42 and, in the case of the inelastic yarn feeding elements, a cam plate 44 and a second cam plate 46, which is illustrated in Figure 14, these being secured together for simultaneous movement. Each ratchet 42 comprises six teeth equiangularly spaced, of which alternate teeth are high, as indicated at 48, the intermediate ones being low, as indicated at 50.

The cam disc or plate 44 contains three cam repeats comprising, respectively, high portions 52, intermediate portions 54 and low portions 56. By reason of the movement of the ratchet one tooth at a time, each cam plate has, in effect, two rest positions which are, respectively, indicated in Figures 4 and 5, one of them involving engagement of the follower 32 by an intermediate height surface 54 and the other involving engagement of the follower by the trailing portion 75

of a high surface 52. To secure proper positioning of the yarn fingers, the cam plates 44 differ slightly in dimensions, but all involve similar high, intermediate and low portions.

The disc 46 is provided with six projections 58 which, as will be pointed out hereafter, serve during movements of the ratchet to effect operation of the individual clamps and cutters associated with the yarn feeding fingers.

In the case of the elastic yarn feeding elements, the ratchet 42 is the same as described, and secured to it is a disc 46, also as described. However, instead of a cam plate 44 there is a cam plate 45 having only what amount to high and low portions 47 and 49, respectively.

As indicated in Figure 1, and following essentially Bentley Patent 1,838,651, there is mounted to oscillate about the axis of the shaft 40 a frame 60 connected through a link 62 to a crank drive 64 which is preferably of the type illustrated and described in detail in the patent to Houseman 2,180,708, dated November 21, 1939, and which permits a shift in timing as described in said patent.

Mounted upon a transverse rod 65 in the frame 60 is a group of pawls 66 numbering seven in all, of which six are arranged to cooperate with the six ratchets 42 corresponding to the six yarn feeding fingers. Each of these seven pawls is 30 provided with a ratchet-engaging hook portion 68 whereby when oscillation of the frame 60 takes place in a counter-clockwise direction in Figure 1, the pawls may ride over the teeth of the ratchets, being thereafter in position to engage the 35 same, if the selective mechanism permits, to rotate the ratchet through one-sixth of a revolution upon clockwise oscillation. Each of the portions is provided with a nose extension 70 arranged to cooperate with the selective mechanism 40 which will be shortly described.

The seventh pawl mentioned above is arranged to cooperate with a ratchet 72 (Figure 15), also journalled upon the shaft or rod 40 and provided with six teeth, which in this case are of equal 45 height. Secured to this ratchet is a cam disc provided with six repeats of cam surfaces involving two high portions 74 and 76. As will be pointed out hereafter, this cam disc is adapted to oscillate the assembly of yarn fingers through the lever 10.

The various ratchet and cam arrangements are essentially the same as described in said Bentley et al. Patent 1,838,651, and are similarly mounted and associated with friction devices for preventing their overrun.

Arranged as in the Bentley patent for endwise sliding movement in the direction of the axis of the shaft 40 and above and slightly to one side thereof is a slide 80, which has its upper end serrated to provide a series of equally spaced high steps 82, five in number, corresponding to the five yarn fingers which are adapted to feed the inelastic yarns. As will be clearest from the diagrams of Figures 10 to 13, inclusive, to the left 60 of these high steps 82, but positioned differently with respect to them, are notches 84, while between the notches and the steps are portions 86 of intermediate level. To the extent so far described, the slide is the same as in said Bentley et al. patent. In the present case, however, this slide carries a second auxiliary slide 88, which is attached thereto for relative sliding movement through the medium of slits 90 embracing studs 92 carried by the slide 80. The auxiliary slide 88 is normally urged toward the right with re-

spect to the slide 80 by means of a spring 94, but is adapted to be moved independently to a limited degree toward the left relative to the main slide 80 against the action of this spring. The auxiliary slide carries a high step 96 of the same height as the steps 82, to the right of which, as viewed in Figures 3 and 10 to 13, there is located a notch 102 which, when the auxiliary slide is in its left hand position relative to the main slide, is in alignment with a notch 104 in the main slide. A second high step 98 is carried by the auxiliary slide and between this and the notch 102 there is the level portion 100, which is also continued to the right of the high step 98.

Referring to Figure 3, there is illustrated there-in the fashion in which the slides are controlled to effect selective actions. A spring 106 urges the slide 80 to the left while movements of the slide to the right are effected through engagement of an adjustable abutment screw 108 carried by the slide 80 by the end of a bell crank 110, connected through a link 112 to a double armed lever 114 provided with a follower portion 116 arranged to ride lugs 118 of various heights on a pattern chain 120 carried by a sprocket wheel secured to a ratchet 122 which is arranged to be moved one step for each course of knitting by means of conventional pawl mechanism which is not illustrated. A series of ratchet wheels may be simultaneously moved by the ratchet 122, all carrying chains for the control of the mechanism. However, one chain may suffice for complete control if it is provided with a series of upstanding lugs on one side for yarn change control and a series of upstanding lugs on the other side for control of the main cam drum of the machine, as well as with lateral lugs indicated at 152 for control of the elastic yarn, as will be described.

For the purpose of controlling the auxiliary slide 88, an upstanding portion 124 thereof at the right of the step 98 is engageable by a wedge-shaped cam 126 carried by the upper end of a lever 128, which is pivoted at 130' to the yarn change bracket of the machine. Also pivoted independently of the lever 128, but on the same center, is a lever 132 which is connected to lever 128 by a spring 134, a suitable stop being provided to limit relative movements of the levers under the spring action. Arranged to abut the lever 132 is a link 136, which is guided at an intermediate portion thereof by pivotal connections to a link 138 and at its forward end is connected to one arm of a bell crank 140, which is pivoted at 142 and has its other end 150 arranged to be engaged by the laterally extending lugs 152 on the pattern chain 120. The pivot at 142 is carried by a lever 144, which is clamped upon the fixed rod 146 with its clockwise position limited and finely adjustable by adjustment of a screw 148 abutting a portion of the frame.

The purpose of the spring arrangements illustrated is to permit the independent movement to the right of the main slide 80 despite the position of the link 136, i. e., while the link 136 is operative to rock the lever 128 and to move the auxiliary slide 88 to the left, acting through the medium of spring 134 against the tensions of springs 130 and 94, the yielding connections prevent jamming under conditions of movement of the slide 88 by the bell crank 110. Spring 130 normally holds cam 126 out of the path of member 124.

Indicated in Figure 3 are certain elements associated with the yarn change mechanism but of conventional type and having no unusual coop-

eration with the matters of the present invention. A collar 113 carried by the rod 112 is arranged to act upon a lever 115 which, through suitable connections, controls both slowing down of the mechanism during yarn changes and the slackening of loops by moving the stitch cam block downwardly, the latter being effected through a lever which is merely indicated at 117 in Figure 1. Both of these controls are conventional in nature. The slackening of loops may take place in the course preceding the change, in the course of the yarn change, and also in the following course. See, for example, Swingehurst Patent 618,017, dated January 17, 1899, and Scott et al. Patent 653,562, dated July 10, 1900.

The operations involved in the changing of yarns may now be described with reference particularly to Figures 4 to 9, inclusive, 10 to 13, inclusive, and 16.

The movements of the inelastic yarn fingers in effecting the introduction of yarns are fundamentally the same as those involved in said Bentley et al. Patent 1,838,651, i. e., the yarn finger first moves in the direction of rotation of the needle cylinders substantially beyond the position which it will later assume during the feed of its yarn, this motion, in fact, being past the line of tangency of a yarn to the needle circle from the clamp in which its end is held. At the end of this extreme movement, the yarn finger moves inwardly toward the axis of the needle cylinder so as to draw the yarn into contact with the needles so that it may be seized by the rising latches of the needles. Immediately thereafter, the yarn finger moves back both away from the needle cylinder and opposite its initial movement in the direction of rotation to come to rest, after again moving inwardly toward the axis, at a position close to the needle circle, but between the region of tangency mentioned above and the position of the clamping and cutting mechanism. It will be obvious, therefore, that from the standpoint of the sliding movement of the fingers as viewed in Figure 1, they will first move from an inactive position of rest to an extreme right hand position, and thereupon immediately back to the position which defines their proper feeding location with respect to the needle circle.

With the above in mind, the positions of the cam discs 44 represented in Figures 4 and 7 correspond to the yarn feeding positions of the fingers which they control. On the other hand, Figures 5, 6 and 8 represent inactive positions of the corresponding yarn feeding fingers. As pointed out above, these two alternatives represent the rest positions of the cam discs. In moving from the position of Figures 4 and 7 to the position of Figures 5, 6 and 8, i. e., in going out of action, follower 32 is merely forced toward the left, representing a simple movement of the yarn finger from feeding position to inactive position slightly beyond its individual clamping and cutting mechanism. On the other hand, the reverse movement between the positions just mentioned involves the dropping of the follower 32 from a high surface 52 to a low surface 56, and its rise to the intermediate surface 54, this giving rise to the extreme forward movement just mentioned followed by a partial retracting movement to the yarn feeding position.

The fashion in which the yarn fingers and their individual clamps and cutters are associated with each other and related to the cylinders at the yarn feeding position is illustrated in Figure 16, in which the needles 153 are shown as

located in the lower cylinder, circumferential directions being considerably exaggerated in this figure for the purpose of clarity, i. e., the needles in seizing the yarn descend at a substantially steeper angle than that shown. With the exception of the elastic yarn feeding finger indicated at 14r, the fingers 14 move forward to an extreme position 14a and then drop back to a feeding position illustrated by the finger 14b, which, in Figure 16, is feeding its yarn to the needles. The details of the movements of the fingers will be described hereafter.

The elastic yarn feeding finger 14r has a different movement produced under the control of the cam 45 illustrated in Figure 9. When a low portion 49 of this cam acts upon the follower 38, the elastic yarn finger is moved to a position approximating that of 14a in Figure 16. But thereafter, instead of being pushed back to the position 14b, it remains in that position so as to lay its yarn between the loops drawn by the upper and lower cylinder needles, the elastic yarn being fed only during rib knitting or, at any rate, only during such times as needles are knitting in both the upper and lower cylinders. The high portions 47 of the cam 45 move the finger 14r to its inactive position, illustrated in Figure 16.

A series of events typical of all of the yarn changing operations is represented by the respective positions of the slides indicated in Figures 10 to 13, inclusive. In these figures, the various extensions or noses 70 of the pawls corresponding to the inelastic yarn feeding fingers are indicated at 70a, 70b, 70c, 70d and 70e, the nose 70 of the pawl corresponding to the elastic yarn feeding finger as indicated at 70r, and the nose of the pawl which controls rocking of the frame 8 is indicated at 78.

In Figure 10, the slides 80 and 88 are located in what may be regarded as a normal position assumed during the continued feeding of any of the yarns. Under these conditions, each of the pawl noses is laterally lined up with a high step 82 or, in the case of the noses corresponding to the elastic yarn feeding finger and the rocking of the bracket 8, the high steps 96 and 98. As a result of this, when the frame 60 oscillates counter-clockwise, the nose of each of the pawls will engage and thereafter ride upon a high step, and in the return oscillation of the frame will continue to engage such step until its hook has passed the location of the engageable face of a corresponding ratchet tooth, so that the hook will merely drop on the circumferential surface of the tooth and effect no action. For the sake of explanation, let it be assumed that the second finger corresponding to the pawl having the nose 70b is feeding yarn while the sliders occupy the positions in Figure 10. Under such conditions, the cam plate 44 corresponding to the second yarn feeding finger is illustrated in Figure 4 and the corresponding pawl 66 at the end of its counter-clockwise movement will also occupy the position illustrated, being raised substantially above a position in which it might engage a high tooth 48 in pulling contact with which, in the absence of the step 82, it could fall.

At the same time, the cams 44, corresponding to the other inelastic yarn feeding fingers, will occupy the position illustrated in Figure 5, and their pawls also will be raised by the high steps 82, or, in the case of the elastic yarn feeding finger, the pawl will engage step 96. Similarly in the case of the rocking mechanism, the pawl carrying the nose 78 will be prevented from en-

gaging any of the teeth on the ratchet 72 by means of the high step 98.

Assume, now, that the fourth of the inelastic yarn feeding fingers, corresponding to the pawl having nose 70d, is to go into action while the yarn corresponding to the nose 70b theretofore feeding is to be removed. To effect this result, after the frame 60 is moved to a substantial extent towards its extreme clockwise position the slide 80 will be moved by a lug 118 of proper height on the chain 120 to the position illustrated in Figure 11. Under these conditions, it will be observed that all of the high steps are moved out of alignment with their respective pawls, and with the exception of the pawl corresponding to the yarn finger which is going in, all of the noses will engage the intermediate levels represented at 86 on the next counterclockwise stroke of the frame 60. The nose 70d, however, will enter the corresponding slot 84, so that the pawl occupies its lowermost position.

Upon clockwise movement of the frame 60, the pawl carrying the nose 70d will move from the position illustrated in Figure 8, and will, consequently, carry the cam engaging the follower 32 of the fourth finger to move it through an angle of 60°. The follower 32 will thereupon be disengaged by surface 52 and thereafter will be engaged by the low surface 56 and the following intermediate height surface 54 to effect a placing of the yarn by the finger and, immediately thereafter, the location of the finger in normal feeding position. It will be noted that this action will locate a high tooth 48 of the corresponding ratchet in position to be engaged upon the next action of the pawl thereon.

The ratchet corresponding to the second finger which was theretofore feeding its yarn will have a high tooth presented for engagement by the 40 pawl so that as the nose 70b of this pawl rides at an intermediate level over ledge 86, the parts will occupy the position illustrated in Figure 7 at the end of the counter-clockwise movement of the frame 60. The pawl is permitted to move 45 sufficiently inwardly to engage a high tooth and consequently, upon clockwise movement of the frame 60, the pawl will impart to the corresponding cam a 60° movement which will serve to retract the second finger from yarn feeding position, moving it to a position beyond its clamp and cutter. At the same time, the cam disc 46, which corresponds thereto will be given a movement which will cause it to cut and clamp the yarn at a time after the new yarn is safely engaged by 50 55 the needles.

In the case of the other inelastic yarn feeding fingers, and the elastic yarn feeding finger, no action occurs by reason of the fact that the position of the ratchet corresponding to any inactive 60 finger involves a presentation in position for possible engagement by the pawl of a low tooth and the engagement of the pawl nose with a surface 86 will prevent the pawl from moving inwardly sufficiently to engage such low tooth. This condition is illustrated in Figure 6, from which it will be evident that the clockwise movement of the frame 60 will fail to produce any movement of any of the ratchets of inactive fingers which are to remain inactive. It may be pointed out that if the machine is properly set up, the advance of the pattern chain will immediately carry from beneath the follower 116 the yarn change compartment of the frame 60, if no yarn change is to take place, the slides moving to the position of Figure

10. Thus there is avoided any possible accidental removal of the introduced yarn which might occur if the slides remain in the same position serving for its introduction. In fact, if it is desired that the machine be completely cleared of yarn, it is only necessary to provide two lugs of the same height on successive links of the pattern chain.

The elastic yarn may be entered at any time while any one of the inelastic yarns remains in action without the removal of that inelastic yarn so that the introduction of the elastic yarn involves a special type of operation. To effect the introduction of the elastic yarn, the slide 80 occupies its normal position, i. e., that of Figure 10, but the auxiliary slide 88 is moved toward the left under the action of a laterally extending lug 152 on the pattern chain. The resulting condition is illustrated in Figure 12, and results in the alignment of the slots 102 and 104 to present a slot through which the nose 70r may project. Assuming that the fourth yarn finger remains in action, it will not be removed from action because of the fact that the conditions existing in Figure 4 will exist, namely, the nose 70d will ride upon a high step 82. As for the other inelastic yarn fingers, they will not be disturbed because in their cases, there will exist the conditions illustrated in Figure 5. In the case of the elastic yarn, however, the condition of Figure 9 will arise, so far as its pawl is concerned, the pawl, dropping into the aligned slots 102 and 104, being in position to engage a low tooth on the corresponding ratchet 42 to step this about and thus bring the yarn finger into action by bringing a low portion 49 of cam 45 into engagement with the follower 38. As the elastic yarn goes into action, its clamp will be opened at the proper time to release the yarn.

The nose 78 of the pawl corresponding to the yarn finger swinging cam will miss the high step 88 riding on the level 100, and accordingly, the swinging of the yarn fingers as a unit will take place to serve for the proper placing of the elastic yarn.

It will be evident that even though the same inelastic yarn remains in feeding position, the elastic yarn may be removed if, after the auxiliary slide is permitted to return so that there exists the condition of Figure 10 for those courses in which the elastic yarn is to remain in action, the auxiliary slide is thereafter moved again to the position of Figure 12. Under such conditions, the nose 70r will again pass through the aligned slots 102 and 104, this time effecting engagement by the pawl of a high step on the ratchet, this condition being illustrated in Figure 9. A high portion 41 is thereby brought opposite follower 38. Thus by successive provisions of laterally extending lugs 152, the elastic yarn may be introduced and removed without affecting the inelastic yarn which is feeding.

Whenever the elastic yarn is feeding, however, it is removed when a yarn change is effected to any inelastic yarn other than the one which is feeding. This condition offers no practical limitation upon the operation of the machine, since practically always if the inelastic yarn which is feeding is to be removed, it is desired simultaneously to remove the elastic yarn. Even if, through a portion of the fabric knit with the substituted inelastic yarn, it is desired to have the elastic yarn also knit, that may be introduced in the next course, leaving only a single course from which the elastic yarn is missing.

The conditions involved in the removal of the elastic yarn when another inelastic yarn, say the

first, is substituted, are illustrated in Figure 13, from which it will be noted that the slide 80 is moved to a position corresponding to the introduction of the first yarn and carries with it the auxiliary slide 88 so that the nose 70r rides at an intermediate level, with the result that the corresponding pawl will engage the high tooth 48 presented by the ratchet corresponding to the elastic yarn. The other operations of removal of the previously knitting inelastic yarn are the same as previously described in detail and need not be repeated.

While reference has been made to an elastic yarn as being specially manipulated, it will be evident that the mechanism may handle any auxiliary yarn which it may be desirable to introduce simultaneously with another yarn with the possibility of making its introductions and removal independent, at least to a major extent, of the changes of the other yarns. Thus, for example, the yarn finger stated as handling the elastic yarn may be used to handle a striping yarn for plating or other decorative or reinforcing purposes, in which case, however, a cam such as 46 would be substituted for cam 45 so that the yarn would be presented for engagement by the needle hooks and not merely laid in as is the elastic yarn.

The clamping and cutting mechanism has been referred to briefly heretofore and in general is substantially identical with that illustrated in Bentley et al. Patent 1,838,651. The various discs 46 associated with the yarn finger controlling ratchets and cams are arranged to act upon adjustable followers 154 carried by horizontally extending arms of levers 156 pivoted at 157. Through Bowden wires 158 passing through tubes 160, levers 162 may be rocked against the tension of suitable springs for the purpose of controlling the individual clamps and cutters indicated generally at 163 and 163', each involving a fixed knife 166, a movable knife and clamping element 164 and a fixed clamping blade 168. When the fingers are in their non-feeding positions, each lies behind its corresponding clamping and cutting mechanism with respect to the feed point. The clamping and cutting mechanisms are arranged in the lower series 163 and the upper series 163' to better conform to the limited space available in view of the large number of yarn carrying fingers, and the desirability of keeping them as close as possible to the yarn feeding position to minimize the yarn ends in the fabric, the clamping and cutting devices 163' being inverted as compared with those at 163 and being controlled through Bowden wires which extend upwardly and then downwardly, as indicated by their tubes 160' in Fig. 1.

The specific mechanism for rocking the bracket 8 is illustrated in Figure 15, in which it will be noted that a follower 170 carried by a lever 172 is acted upon by the cam having the various high portions 74 and 76 previously described. The lever 172 is pivoted at 174 and is provided with an adjustable abutment screw 176 bearing on the arm 10 and arranged to move it to an extent limited by a fixed adjustable abutment screw 178. This mechanism is the same as that described in said Bentley et al. patent.

It is found that, by reason of the different locations of the several clamping and cutting means and of the yarn fingers in their inactive positions, during the entry and also during the removal of yarns the paths which the yarns would take without special precautions differ to such ex-

tent that either misplacement of the yarns may occur or there may be too early a withdrawal of a yarn. In order to avoid this condition, there is secured to the fixed latch guard 180, which terminates just above the position of the needle hooks when they are about to seize the yarn, a wire loop 182 extending radially outwardly as indicated in Figure 16. By reason of the provision of this loop, the line of approach of the yarns to the needles is held low to insure that the yarn is inevitably introduced below their hooks. In other words, the yarn extending during the entry period of the yarn from any of the upper clamps will occupy the same path with respect to the needles which are to seize it. Likewise, as a yarn is withdrawn, it will occupy substantially the same path with respect to the needles which are last to take it, irrespective of the ultimate fully withdrawn position of a yarn finger.

The motions of the various fingers may now be described in detail. Considering first changes involving the inelastic yarn feeding fingers, the first event occurring in a yarn change involves the pushing out of the finger which is feeding by the action of the steep climb between the surfaces 54 and 52 of its cam 44. This finger is thus forced to its normal inactive position, but continues to feed its yarn to the needles with no interruption whatever of the feeding action, the wire loop 182 serving to guide the yarn in proper fashion in the case of the upper bank of fingers.

The next event is the dropping of the follower 170 off the long high surface 74 of the cam illustrated in Figure 15, which controls the swiveling of the bracket 8 (Figure 1) supporting the yarn fingers. Swinging of this bracket occurs, moving the ends of the yarn fingers outwardly to provide clearance during the next movement.

The finger selected to go into action now moves to the extreme forward position 14a, dipping en route, because of the shape of the slot 20 in which its pin 18 rides, to clear the wire loop 182.

One of the short high surfaces 76 of the swivel controlling cam now acts upon the follower 170 to swing the bracket 8 so as to carry the yarn fingers inwardly, and in particular the one which has just moved to its extreme forward position. This inward movement occupies the time of passage of two or three needles and results in seizure of the yarn by these needles, the yarn being guided, in the case of each upper yarn, by the wire loop 182 at a proper level, extending thereunder to the finger from the corresponding clamp.

Except for the clamp for the upper right hand finger in Figure 16, the clamps have their openings facing the needles. The clamp for the upper right finger is an exception, its clamp facing away from the needles. This allows later closing of this clamp and cutter in order to make sure that the yarns overlap in the fabric at the change. This finger is so close to the knitting point that a later closing of the clamp and cutter is necessary to insure this overlap.

The action of the clamps is as follows for all 65 except the upper right clamp:

The clamp for the yarn going into action is immediately opened, and at the same time, the clamp for the yarn which is going out of action is opened. The follower 170 substantially simultaneously is released by the cam surface 76, and consequently the finger assembly again swings outwardly. Immediately thereafter, the finger which is going into action is moved back to the feeding position 14b, this action taking place by 75

reason of the rise from a low surface 56 to an intermediate surface 54 of its cam 44. In view of the fact that it has been swung outwardly, it will clear the needle latches in this movement. It will also dip to clear the wire loop 182 due to the form of its cam slot 20.

Finally, the follower 170 is again engaged by a surface 74, with the result that the yarn fingers are swung inwardly and at this time the outgoing yarn, which has been feeding through its clamp and cutter, is cut. However, in the case of the upper right finger, its yarn is thrown into its clamp and cutter as it moves inwardly, the movable element moving to cut and clamp this yarn at its furthest inward motion instead of at the beginning of this inward motion, as in the case of the other fingers.

The cutter and clamp for any other finger may be faced outwardly to provide a longer overlap if found desirable.

All of these various events take place in a very short period to effect a rapid yarn change with a short, but sufficient, overlap of the outgoing and incoming yarns to prevent opening of the fabric. 25 As indicated above, the close proximity of all of the yarn fingers to the feed point avoids the presence of long yarn ends.

In the case of the elastic yarn finger's going into action, a quite similar cycle takes place, with 30 the exception that at the end of this cycle the elastic yarn finger 14r occupies a position approximately as illustrated at 14a just beyond the lowermost point of the stitch cam, so that it may lay its yarn between the loops drawn by the 35 needles in the upper and lower cylinder. As this finger goes into action, its dipping movement causes it to clear the yarn finger which is in feeding position. As it moves forwardly, and up to the time the elastic yarn is released by its 40 clamp, the elastic yarn is fed within the needle hooks. Just as in the case of an ingoing inelastic yarn, with the result that it is actually knitted into a group of stitches whereby its end is held from movement relative to the fabric. Until it is again removed, however, it merely falls into the crotches of the stitches as described. When it goes out, it is again caught by the needles and knitted into the loops, with the result that both ends of the portion fed to the fabric are 45 securely tied therein.

The sinkers in the present machine are specially constructed to improve the handling of the yarns in two respects, first to accelerate the seizure of an ingoing yarn, and secondly to insure 55 that as needles are picked down into action the loops on the shanks thereof will not be carried below the sinker hooks.

The double ended needles 153 heretofore indicated are provided with upper hooks, indicated at 190 and upper latches at 192 and are of conventional form. The sinkers 194 are also substantially conventional, being arcuate in form and arranged to move in circular arcs about centers concentric with their shank portions. Each of the sinkers is provided with a hook 196 in usual position, but is also provided inwardly of the hook with a hump portion 198 projecting substantially above the arc 202 which would continue the throat portion 204 beneath the hook. Each sinker is also provided with an extended nose 200 as contrasted with conventional sinkers which terminate just outwardly of the hook.

The action of the sinker in accelerating the seizure of a yarn Y will be evident from the successive steps of operation indicated in Figures

17, 18 and 19. Normally, the loops would lie approximately at the level of the arc indicated at 202, but prior to the descent of the needle to seize the yarn and draw stitches, the sinker moves outwardly, so that the hump 198 cams upwardly the loops held by the needles. As the descent of a needle begins, the latch immediately engages the loop on the shank of its needle, with the result that it is very quickly flipped upwardly to trap the incoming yarn Y. As will be evident from Figures 17 and 18, the entrapment of the yarn will take place with a very slight descending movement of a needle corresponding to a short angular movement about the axis of the needle cylinder. As the needle moves to its lowermost position, the adjacent sinkers move inwardly so that the stitches are drawn over the outer portion of the ledge 198 or substantially in the throat 204.

Figures 20 and 21 illustrate the fashion in which the nose of the sinker prevents the loops from getting too low as the needles are picked down into action in the formation of heels and toes.

As is conventional, each of the needles has a hump 206 located beneath the latch, and when a needle is picked up out of action, the hump 206 will lie above the level of a loop L about its shank. At this same time, the stitch will be above the hook of the sinker due to the action of the associated conventional bluff sliders. Accordingly, if the needle was then lowered, the hump 206 would, by frictional action, tend to pull it downwardly into such position that it might be drawn below the nose of the sinker, which, on being projected, might penetrate the loop. Provision of the extended nose 208 on the sinker prevents this action, insuring that the loop remains above the sinker at all times.

What we claim and desire to protect by Letters Patent is:

1. A knitting machine comprising a series of needles, a plurality of means for presenting yarns to said needles, and yarn changing devices, said yarn changing devices comprising a main selector element, means for moving said selector element to various positions to determine yarn changes, and an auxiliary selector element movable independently of the main selector element to effect auxiliary yarn changes, said auxiliary selector element being movable with the main selector element so that, upon operation of the main selector element to effect a yarn change, the auxiliary yarn is removed from feeding position.

2. A knitting machine comprising a series of needles, a plurality of means for presenting yarns to said needles, and yarn changing devices, said yarn changing devices comprising a main selector element, means for moving said selector element to various positions to determine yarn changes, and an auxiliary selector element movable independently of the main selector element to effect auxiliary yarn changes without effecting changes of yarns under the control of the main selector element, said auxiliary selector element being movable with the main selector element so that, upon operation of the main selector element to effect a yarn change, the auxiliary yarn is removed from feeding position.

3. A knitting machine comprising a series of needles, a plurality of means for presenting yarns to said needles, and yarn changing devices, said yarn changing devices comprising a main selector slide, means for moving said main selector slide to various positions to determine yarn

changes, and an auxiliary selector slide carried by the main selector slide but movable independently thereof to effect auxiliary yarn changes.

4. A knitting machine comprising a series of needles, a plurality of means for presenting yarns to said needles, and yarn changing devices, said yarn changing devices comprising a main selector slide, means for moving said main selector slide to various positions to determine yarn changes, and an auxiliary selector slide carried by the main selector slide but movable independently thereof to effect auxiliary yarn changes without effecting changes of yarns under the control of the main slide.

5. A knitting machine comprising a series of needles, a plurality of means for presenting yarns to said needles, and yarn changing devices, said yarn changing devices comprising a main selector slide, means for moving said main selector slide to various positions to determine yarn changes, and an auxiliary selector slide carried by the main selector slide but movable independently thereof to effect auxiliary yarn changes, said auxiliary selector slide being movable with the main selector slide so that, upon operation of the main slide to effect a yarn change, the auxiliary yarn is removed from feeding position.

6. A knitting machine comprising a series of needles, a plurality of means for presenting yarns to said needles, and yarn changing devices, said yarn changing devices comprising a main selector slide, means for moving said main selector slide to various positions to determine yarn changes, and an auxiliary selector slide carried by the main selector slide but movable independently thereof to effect auxiliary yarn changes without effecting changes of yarns under the control of the main slide, said auxiliary selector slide being movable with the main selector slide so that, upon operation of the main slide to effect a yarn change, the auxiliary yarn is removed from feeding position.

7. A knitting machine comprising a series of needles arranged to knit fabric containing reversely concatenated loops, a plurality of means for presenting yarns to said needles to be knit into stitches, means for presenting a yarn to said needles to be held between reversely concatenated loops, and yarn changing devices comprising a main selector element, means for moving said selector element to various positions to determine changes of the first mentioned yarns, and an auxiliary selector element movable independently of the main selector element to effect changes of the last mentioned yarn, without effecting changes of yarns under control of the main selector element, said auxiliary selector element being movable with the main selector element so that, upon operation of the main selector element to effect a yarn change, the last mentioned yarn is removed from feeding position.

8. A knitting machine comprising a series of needles arranged to knit fabric containing reversely concatenated loops, a plurality of means for presenting yarns to said needles to be knit into stitches, means for presenting a yarn to said needles to be held between reversely concatenated loops, and yarn changing devices comprising a main selector element, means for moving said selector element to various positions to determine changes of the first mentioned yarns, and an auxiliary selector element movable independently of the main selector element to effect changes of the last mentioned yarn, without effecting

changes of yarns under control of the main selector element, said auxiliary selector element being movable with the main selector element so that, upon operation of the main selector element to effect a yarn change, the last mentioned yarn is removed from feeding position.

9. A knitting machine comprising a series of needles, a plurality of fingers for presenting yarns to said needles, and individual clamps and cutters for said yarns, said clamps and cutters being arranged in a plurality of banks and said yarn presenting fingers occupying inoperative positions adjacent to their respective clamps and cutters and being movable between said banks towards and away from yarn feeding positions.

10. A knitting machine comprising a series of needles, a plurality of fingers for presenting yarns to said needles, individual clamps and cutters for said yarns, said clamps and cutters being arranged in a plurality of banks and said yarn presenting fingers occupying inoperative positions adjacent to their respective clamps and cutters, and yarn guiding means engaging the yarns from fingers of one of said banks to guide the same to the needles.

11. A knitting machine comprising a series of needles, a plurality of fingers for presenting yarns to said needles, individual clamps and cutters for said yarns, said clamps and cutters being arranged in a plurality of banks and said yarn presenting fingers occupying inoperative positions adjacent to their respective clamps and cutters, and yarn guiding means engaging yarns from fingers of one of said banks between the feeding positions of their fingers and the point of seizure of the yarns by the needles to guide the same to the needles.

12. A knitting machine comprising a series of needles, a plurality of fingers for presenting yarns to said needles, individual clamps for said yarns, said clamps being arranged in a plurality of banks and said yarn presenting fingers occupying inoperative positions adjacent to their respective clamps and being movable between said banks towards and away from yarn feeding positions.

13. A knitting machine comprising a series of needles, a plurality of fingers for presenting yarns to said needles, individual clamps for said yarns, said clamps being arranged in a plurality of banks and said yarn presenting fingers occupying inoperative positions adjacent to their respective clamps, and yarn guiding means engaging yarns from fingers of one of said banks to guide the same to the needles.

14. A knitting machine comprising a series of needles, a plurality of fingers for presenting yarns to said needles, individual clamps for said yarns, said clamps being arranged in a plurality of banks and said yarn presenting fingers occupying inoperative positions adjacent to their respective clamps, and yarn guiding means engaging yarns from fingers of one of said banks between the feeding positions of their fingers and the point of seizure of the yarns by the needles to guide the same to the needles.

15. A knitting machine comprising a series of needles, a plurality of fingers for presenting yarns to said needles, individual clamps and cutters for said yarns, said clamps and cutters being arranged in a plurality of banks and said yarn presenting fingers being movable between said banks towards and away from yarn feeding positions.

16. A knitting machine comprising a series of

needles, a plurality of fingers for presenting yarns to said needles, individual clamps and cutters for said yarns, said clamps and cutters being arranged in a plurality of banks, and yarn guiding means engaging the yarns from fingers of one of said banks to guide the same to the needles.

17. A knitting machine comprising a series of needles, a plurality of fingers for presenting yarns to said needles, individual clamps and cutters for said yarns, said clamps and cutters being arranged in a plurality of banks, and yarn guiding means engaging yarns from fingers of one of said banks between the feeding positions of their fingers and the point of seizure of the yarns by the needles to guide the same to the needles.

18. A knitting machine comprising a series of needles, a plurality of fingers for presenting yarns to said needles, and individual clamps for said yarns, said clamps being arranged in a plurality of banks and said yarn presenting fingers being movable between said banks towards and away from yarn feeding positions.

19. A knitting machine comprising a series of needles, a plurality of fingers for presenting yarns to said needles, individual clamps for said yarns, said clamps being arranged in a plurality of banks, and yarn guiding means engaging yarns from fingers of one of said banks to guide the same to the needles.

20. A knitting machine comprising a series of needles, a plurality of fingers for presenting yarns to said needles, individual clamps for said yarns, said clamps being arranged in a plurality of banks, and yarn guiding means engaging yarns from fingers of one of said banks between the feeding positions of their fingers and the point of seizure of the yarns by the needles to guide the same to the needles.

21. A knitting machine comprising a series of needles, a plurality of means for presenting yarns to said needles, and yarn changing devices, said yarn changing devices comprising a main selector element, means including a pattern device for moving said selector element to various positions to determine yarn changes, an auxiliary selector element movable independently of the main selector element to effect auxiliary yarn changes, and means including a second pattern device for moving said auxiliary selector element, said auxiliary selector element being movable also by the first mentioned pattern device.

22. A knitting machine comprising a series of needles, a plurality of means for presenting yarns to said needles, and yarn changing devices, said yarn changing devices comprising a main selector element, means for moving said selector element to various positions to determine yarn changes, and an auxiliary selector element movable independently of the main selector element to effect auxiliary yarn changes, said auxiliary selector element being also movable with the main selector element.

23. A knitting machine comprising a series of needles, a plurality of means for presenting yarns to said needles, and yarn changing devices, said yarn changing devices comprising a main selector element, means for moving said main selector element to various positions to determine yarn changes, and an auxiliary selector element carried by the main selector element but movable independently thereof to effect auxiliary yarn changes.

24. A knitting machine comprising a series of needles arranged to knit fabric containing re-

versely concatenated loops, a plurality of means for presenting yarns to said needles to be knit into stitches, means for presenting a yarn to said needles to be held between reversely concatenated loops, and yarn changing devices comprising a main selector element, means for moving said selector element to various positions to determine changes of the first mentioned yarns, and an auxiliary selector element movable independently of the main selector element to effect changes of the last mentioned yarn, said auxiliary selector element being also movable with the main selector element.

25. A knitting machine comprising a series of needles arranged to knit fabric containing reversely concatenated loops, a plurality of means for presenting yarns to said needles to be knit into stitches, means for presenting a yarn to said needles to be held between reversely concatenated loops, and yarn changing devices comprising a main selector element, means for moving said selector element to various positions to determine changes of the first mentioned yarns, and an auxiliary selector element movable independently of the main selector element to effect changes of the last mentioned yarn, without effecting changes of yarns under control of the main selector element, said auxiliary selector element being also movable with the main selector element.

26. A knitting machine comprising a series of needles, a plurality of means for presenting yarns to said needles, and yarn changing devices, said yarn changing devices comprising a main selector element, means including a pattern device for moving said selector element to various positions to determine yarn changes, an auxiliary selector element controllable at will either by the main selector element or independently thereof to effect auxiliary yarn changes, and means including a second pattern device for controlling said auxiliary selector element independently of the main selector element.

27. A knitting machine comprising a series of needles, a plurality of means for presenting yarns to said needles, and yarn changing devices, said yarn changing devices comprising a main selector element, means for moving said selector element to various positions to determine yarn changes, and an auxiliary selector element controllable at will either by the main selector element or independently thereof to effect auxiliary yarn changes.

28. A knitting machine comprising a series of needles arranged to knit fabric containing reversely concatenated loops, a plurality of means for presenting yarns to said needles to be knit into stitches, means for presenting a yarn to said needles to be held between reversely concatenated loops, and yarn changing devices comprising a main selector element, means for moving said selector element to various positions to determine changes of the first mentioned yarns, and an auxiliary selector element controllable at will either by the main selector element or independently thereof to effect changes of the last mentioned yarn.

29. A rotary knitting machine comprising a series of needles, a finger for presenting a yarn to the needles, a clamp for said yarn, said finger having an inactive position adjacent to its clamp in which it temporarily feeds its yarn from a point in a plane, perpendicular to the axis of rotation, displaced substantially, in a direction opposite that of yarn-taking needle movements, from the

point from which it normally feeds its yarn, and yarn guiding means engaging said yarn between its finger and the needles as the finger moves from the second mentioned point to the first adjacent its clamp preparatory to yarn change.

30. A rotary knitting machine comprising a series of needles, a finger for presenting a yarn to the needles, a clamp for said yarn, said finger having an inactive position adjacent to its clamp in which it temporarily feeds its yarn from a point in a plane, perpendicular to the axis of rotation, displaced substantially from the point from which it normally feeds its yarn, and yarn guiding means engaging said yarn between its finger and the needles as the finger moves from the second mentioned point to the first adjacent its clamp preparatory to yarn change to maintain proper approach of the yarn to the needles.

31. A rotary knitting machine comprising a series of needles, a finger for presenting a yarn to the needles, a clamp for said yarn, said finger having an inactive position adjacent to its clamp in which it temporarily feeds its yarn from a point in a plane, perpendicular to the axis of rotation, displaced substantially from the point from which it normally feeds its yarn, yarn guiding means engaging said yarn between its finger and the needles as the finger moves from the second mentioned point to the first adjacent its clamp preparatory to yarn change to maintain proper approach of the yarn to the needles, and means for moving the finger from active to inactive position in a path avoiding contact with said yarn guiding means.

32. A knitting machine comprising a series of needles, a plurality of fingers for presenting yarns to said needles, individual clamps for said yarns, said clamps and fingers being arranged in a plurality of banks, and yarn guiding means engaging yarns fed by the fingers of one of said banks between their fingers and the needles as the fingers move away from their yarn feeding position to positions adjacent to their clamps preparatory to yarn change.

33. A knitting machine comprising a series of needles, a plurality of fingers for presenting yarns to said needles, individual clamps for said yarns, said clamps being arranged in a plurality of banks and said yarn presenting fingers being movable between said banks towards and away from yarn feeding positions, and yarn changing devices, said yarn changing devices comprising a main selector element, means for moving said selector element to various positions to determine yarn changes, and an auxiliary selector element movable independently of the main selector element to effect auxiliary yarn changes, said auxiliary selector element being also movable with the main selector element.

34. A knitting machine comprising a series of needles, a plurality of fingers for presenting yarns to said needles, individual clamps for said yarns, said clamps being arranged in a plurality of banks and said yarn presenting fingers being movable between said banks towards and away from yarn feeding positions, and yarn changing devices, said yarn changing devices comprising a main selector element, means for moving said selector element to various positions to determine yarn changes, and an auxiliary selector element carried by the main selector element but movable independently thereof to effect auxiliary yarn changes.

35. A knitting machine comprising a series of needles, a plurality of fingers for presenting yarns to said needles, individual clamps for said yarns,

said clamps being arranged in a plurality of banks, yarn guiding means engaging yarns from fingers of one of said banks to guide the same to the needles, and yarn changing devices, said yarn changing devices comprising a main selector element, means for moving said selector element to various positions to determine yarn changes, and an auxiliary selector element movable independently of the main selector element to effect auxiliary yarn changes, said auxiliary selector element being also movable within the main selector element.

36. A knitting machine comprising a series of needles, a plurality of fingers for presenting yarns to said needles, individual clamps for said yarns, said clamps being arranged in a plurality of banks, yarn guiding means engaging yarns from fingers of one of said banks to guide the same to the needles, and yarn changing devices, said yarn changing devices comprising a main selector element, means for moving said selector element to various positions to determine yarn changes, and an auxiliary selector element carried by the main selector element but movable independently thereof to effect auxiliary yarn changes.

37. A knitting machine comprising a series of needles, a plurality of fingers for presenting yarns to said needles, individual clamps for said yarns, yarn guiding means engaging yarns between their fingers and the needles as the fingers move away from their yarn feeding positions to positions adjacent to their clamps preparatory to yarn change, and yarn changing devices, said yarn changing devices comprising a main selector element, means

for moving said selector element to various positions to determine yarn changes, and an auxiliary selector element movable independently of the main selector element to effect auxiliary yarn changes, said auxiliary selector element being also movable with the main selector element.

38. A knitting machine comprising a series of needles, a plurality of fingers for presenting yarns to said needles, individual clamps for said yarns, yarn guiding means engaging yarns between their fingers and the needles as the fingers move away from their yarn feeding positions to positions adjacent to their clamps preparatory to yarn change, and yarn changing devices, said yarn changing devices comprising a main selector element, means for moving said selector element to various positions to determine yarn changes, and an auxiliary selector element carried by the main selector element but movable independently thereof to effect auxiliary yarn changes.

39. A knitting machine of double cylinder type comprising a series of needles, a finger for presenting a yarn to the needles, a clamp for said yarn, said finger having different operating positions from which it may feed yarn, which positions are such that direct lines of approach of yarn from the finger positions to the needles would be different, and guiding means engaging said yarn between the finger and the needles to cause the yarn to follow substantially the same path from the guiding means to the needles irrespective of the position of the yarn feeding finger.
